DUAL TIME CONTROL DEVICE

Gustav Klein, Melrose Park, Pa.

Application October 8, 1945, Serial No. 621,089

5 Claims. (Cl. 161—1)

1

My invention relates to a dual time control device adapted to activate or inactivate a separate and independently operating apparatus at the beginning or at the end of two unequal time intervals.

The main object of the invention is to produce an improved control device of the type set forth.

A further object is to produce an inexpensive, attractive and easily operable dual control device.

A still further object is to produce a control device in which the different time measuring devices employed are encased in a single housing and are operable from one point whereby a compact device can be conveniently located and used even where available space is limited.

These and other objects are effected by my invention as will be apparent from the following description and claims taken in connection with the accompanying drawings, forming a part of this application, in which:

Fig. 1 is a diagrammatic plan view of a dual time control device embodying the invention;

Fig. 2 is a front elevational view of the same;

Fig. 3 is a section on line 3—3 of Fig. 1;

Fig. 4 is a section on line 4—4 of Fig. 3, certain parts being omitted; and

Figs. 5 and 6 are similar to Fig. 4, showing different adjustments.

Referring to the drawings, 10 designates a casing of any suitable size and shape, the front wall of which is inscribed with suitable indicia to provide an inner dial 12 and an outer dial 14. One of the dials, such as the outer dial 14, is designed to indicate the passage of time in terms of hours and the other dial is designed to indicate the passage of time in terms of minutes.

Within the casing are a pair of time-measuring devices 16 and 18, which are suitably positioned within the casing by brackets or the like 20. The time-measuring devices 16 and 18 are of a type now available on the market and known as "Minute minder." Briefly, a device of this type includes a clock mechanism adapted to be wound by rotation of a shaft attached to the spring, and are so constructed that, as soon as the shaft is released, the clock mechanism is set in motion by the unwinding of the spring. The angular displacement of the shaft, or the extent to which it is rotated, determines the length of time that will elapse before the clock spring is completely unwound. Time-measuring devices of this type also include a knob for rotation of the shaft, a dial, and an index for indicating the extent to which the shaft has been rotated. For example, if the shaft has been rotated until the index reg-

isters with numeral 15 on the dial, it means that the clock mechanism will be in motion for a period of fifteen minutes, and so on. It is believed that, with this explanation, it is not necessary to show the clock mechanisms in detail.

In order to carry out the present invention, the time-measuring devices 16 and 18 are placed in alignment with reference to the dials and are provided with nested, concentric actuating shafts. As will be seen from Figs. 1 and 3, the rear device 16 is actuated by a shaft 22 which extends through a sleeve or hollow shaft 24 which actuates the device 18. The shafts 22 and 24 extend through the front wall of the casing and have concentric actuating knobs 26 and 28, respectively. The knob 26 carries a long index or pointer 30 for coacting with the outer dial 14, and the knob 28 carries a short index 32 for coacting with the inner dial 12.

The shafts 22 and 24 also carry fixedly-secured discs 34 and 36, respectively, which rotate with their respective shafts and which are provided with gradually rising cam surfaces 38 and 40. Coacting with the cams 34 and 36 is an arm 42 which is pivoted at one end thereof, as at 44, and which carries a pin 46 adapted to overlie the cams 34 and 36, as best seen from Figs. 1 and 3. The free end of the arm 42 is operatively connected to an apparatus to be controlled, the connection being such that, whenever the free end of the arm 42 is raised, the apparatus referred to is set in motion or stopped, or its operation or condition is otherwise modified. For example, the free end of the arm could, upon being raised and lowered, open or close a switch, open or close a valve, or perform other useful work. Since the apparatus to be controlled forms no part of the present invention, no special type of such apparatus is shown or described.

Operation

When the time control device is inactive, as shown in Figs. 2 and 4, the pointers 30 and 32 and the high points 38 and 40 of the cams are in alignment. This represents the normal or "zero" position, in which the springs of both of the time measuring devices are completely unwound. In this position, the pin 46 is to the left of the cam surfaces 38 and 40 as viewed in Fig. 4. When the shafts 22 and 24 are turned in counterclockwise direction as viewed in Fig. 4, the high cam surfaces will pass under the pin 46 and thus raise the arm 42 momentarily. The pin 46 now rides on the circular rim of the cam discs to the right of the cam surfaces, as viewed in Fig. 4. As the

springs of the time measuring devices 16 and 18 unwind, the discs will turn in clockwise direction until the cam surfaces again pass under the pin 46 and raise the arm 42. For example, if the knob 28 is turned until the pointer 32 registers with the numeral 3 on the inner dial 12, the time measuring device 16 is wound so as to run for a period of three minutes, and after the passage of three minutes, the arm 42 will be raised by the cam 38. Also, if the knob 26 is turned until the pointer 30 registers with the numeral 3 on the outer dial 14, the time measuring device 18 will be wound so as to run for a period of three hours, and, after the passage of three hours, the cam surface 40 will pass under and raise the arm 42.

In Fig. 5, the discs are shown in the position they will assume when the apparatus has been set to operate after the lapse of two unequal intervals of time. It will be noted that the cam surfaces 38 and 40 are to the left of, and unequally, angularly spaced from the axis of the pin 46.

In Fig. 6, the apparatus is shown at about the moment of expiration of the shorter interval of time and the cam 38 is passing under the pin 46 and raising the arm 42. After a further lapse of time, the cam 40 will likewise pass under and again raise the arm 42. When this takes place, the springs of the time mechanisms are unwound and the knobs and pointers are again in the starting or zero position of Fig. 4. If desired, a stop 48 may be used for locating the starting position and for preventing the operator from inadvertently turning the knobs in the wrong direction.

It will be understood from the foregoing that each of the time-measuring devices may be set and used separately but that they coact to produce a multiple control whereby any given operation can be controlled with reference to the passage of time. For example, if it is desired to apply a heat of a given value to some apparatus for a given period of time and then to apply heat of a lower or higher value for a longer or shorter period of time, the movable member is connected to a switch or a valve supplying or controlling the supply of heat, and the time-measuring devices are adjusted to actuate the movable member upon the passage of the desired time intervals.

It will also be noted that the time-measuring devices are longitudinally aligned and that the concentric shafts are normal thereto, so that a very compact and neat apparatus is produced which can be readily applied to a cooking range

or the like without excessive cost and without occupying too much space or detracting from the appearance of said stove.

What I claim is:

5 1. A dual time control apparatus including a plurality of time-measuring devices, a corresponding plurality of concentric shafts, said shafts being separately rotatable in one direction to set said devices to measure predetermined periods of time, respectively, each of said shafts being rotatable in the reverse direction by the time-measuring action of its corresponding device, a disc rotatable with each of said shafts and having a cam surface thereon, and a movable member disposed adjacent said discs and adapted to be actuated by passage of said cam surfaces past said member.

2. A dual time control apparatus including a plurality of spring-actuated time-measuring devices, a plurality of concentric shafts, said shafts being separately rotatable in one direction to set said devices to measure predetermined periods of time, respectively, each of said shafts being rotatable in the reverse direction by the time-measuring action of its corresponding device, a disc rotatable with each of said shafts and having a high cam surface thereon, and a movable member disposed adjacent said discs and adapted to be raised and lowered by passage of said cam surfaces past said member.

3. The structure recited in claim 1 together with concentric dials calibrated to indicate different time intervals and pointers movable with said shafts and coacting with said dials.

35 4. The structure recited in claim 1 together with a finger carried by said movable member and extending transversely of the peripheries of said discs, said finger being raised by passage of said cam surfaces to raise said movable member.

40 5. The structure recited in claim 1 in which said time-measuring devices are aligned longitudinally of the axes of said shafts and are housed in a single casing through a wall of which said shafts extend.
